UNITED STATES PATENT OFFICE.

JAMES HORRIDGE, OF BOLTON, ENGLAND, ASSIGNOR TO JOHN HETHERINGTON AND SONS LIMITED, OF MANCHESTER, ENGLAND.

MACHINE FOR COMBING COTTON AND THE LIKE.

Application filed March 28, 1922. Serial No. 547,356.

To all whom it may concern:

Be it known that I, JAMES HORRIDGE, a subject of the King of Great Britain, residing at 261 Derby Street, Bolton, in the county of Lancaster, England, have invented new and useful Improvements in Machines for Combing Cotton and the like, of which the following is a specification.

The invention relates to improvements in or relating to machines for combing cotton and the like and has for its object to improve the method of actuating the detaching rollers and to provide simple mechanism therefor.

15 In combing machines of the Heilman type it is customary to employ a group of three detaching rollers while in those of the Nasmith type four detaching rollers are usually employed.

20 In the former case, as is well understood, one of the three rollers is a prime mover and transmits its motion by frictional contact to the other two rollers whereas in the Nasmith machine the two bottom rollers are

25 geared together while the upper rollers are driven by their respective bottom rollers by frictional contact.

Hitherto it has been customary to impart to said detaching rollers a partial reverse 30 and subsequent forward movement and for this purpose it has been necessary to employ various somewhat complicated arrangements of mechanism.

Now according to the present invention 35 said partial reverse movement of the detaching rollers and the consequent complicated arrangement of mechanism are dispensed with and the following method and mechanism are employed for performing the detaching operation.

For the purpose of this invention preferably four detaching rollers are employed as in the Nasmith machine and the lower one of the front rollers is continuously 45 rotated in a forward direction and the lower back roller is intermittently rotated in a forward direction which imparts to the cotton under treatment the action and movement hereinafter described.

50 The front end of the lap is fed forward by the combined action of the feed rollers and nippers as at present to the continuously rotating front detaching rollers which draw off the combed fibres and the piecing of the

fibres is carried out between the front and back detaching rollers in the following manner.

As the front rollers draw off the combed fibres and continue to rotate they place the front ends of the combed fibres between the nip of the back rollers at which moment the back rollers commence to rotate in a forward direction drawing with them the fibres and after a certain amount of movement has taken place the back rollers stop while the front rollers continue to rotate and the back end of the fibres continues to advance which causes the same to buckle and the back end thereof to fall down between the front rollers and the back rollers leaving a length 70 of cotton for the next delivery to overlap thus making the piecing.

Any suitable gearing may be employed for driving the front rollers continuously and the back rollers intermittently from the cylinder shaft but the following mechanism is that which is preferred to employ for that purpose.

In the accompanying drawings—

Figure 1 is an end elevation of gearing 80 suitable for driving the front and back detaching rollers in accordance with the present invention.

Figure 2 is a diagrammatic side view 85 thereof and

Figures 3, 4 and 5 are diagrams illustrating three phases of the detaching and piecing operations carried out in accordance with the present invention.

Referring to Figures 1 and 2, 1 represents 90 a portion of the frame of the machine, 2 represents the cylinder, 3 represents the cylinder shaft, 4 represents a portion of the driving wheel, 5, 5^a represent the front detaching rollers and 6, 6^a represent the back 95 detaching rollers.

The front detaching roller 5 is continuously driven from the cylinder shaft 3 by the following means. Upon said shaft 3 is fixed a spur wheel 7 which gears with an idler spur wheel 8 mounted upon a boss 9 mounted for rotation upon a shaft 10 carried by the frame 1 of the machine and upon the boss 9 is also mounted another idler spur wheel 11 which gears with a pinion 12 fixed upon the shaft 5^x of the front detaching roller 5 said shaft being extended for that purpose as shown.

The back detaching roller 6 is intermittently driven from the cylinder shaft 3 by the following means. Upon the boss 4^a of the driving wheel 4 is a pin 13 and upon 5 one end of a short shaft 14 revolvably mounted in the frame 1 of the machine is a star wheel 15 while upon the other end of the shaft 14 is fixed a spur wheel 16 which gears with an idler pinion 17 mounted upon a stud 10 18 carried by the frame 1 and said pinion 17 is of such width and is so arranged that it gears with and drives an idler spur wheel 19 mounted upon the shaft 10, and upon the shaft 6^a of the back roller 6, which is extended for that purpose, is a spur wheel 15 or pinion 20 with which the spur wheel 19 gears and drives.

Once in every revolution of the boss 4^a the pin 13 engages the star wheel 15 and 20 imparts thereto and consequently to the spur wheel 16 a partial revolution which intermittent motion is communicated by the spur wheel 16 to the pinion 17 and through the spur wheels 19 and 20 to the back 25 roller 6.

In the diagram Figures 3, 4 and 5 *x* represents the nippers of the combing machine, and *y* and *z* represent tufts of cotton.

In Figure 3 the nippers *x* are shown presenting the tuft of cotton *y* to the front continuously rotating detaching rollers 5, 5^a the preceding tuft *z* being in the nip of the back detaching rollers 6, 6^a which are assumed to be momentarily at rest.

35 Upon nipping the tuft *y* the continuously rotating rollers 5, 5^a carry it into the position illustrated at Figure 4 where it meets the tuft *z* at the nip of the back detaching rollers 6, 6^a which now rotate and effect the 40 piecing and continue to rotate until the whole of the tuft *z* has passed through the nip of said rollers 6, 6^a at which point the rotation of the same ceases while the front rollers 5, 5^a continue to rotate.

45 The effect of this action is that the tuft *y* buckles between the rollers 5 and 6 as shown in Figure 5 and its rear end follows the periphery of the roller 5 in its movement and finally assumes the position occu-

50 pied by the tuft *z* in Figure 3 and the cycle of operations above described is repeated.

From the foregoing it will be observed that the piecing operation is performed at a point between the front and back detaching rollers instead of at a point in front of 55 the front detaching rollers and that by imparting to said rollers a continuous rotary motion in a forward direction and to the back rollers an intermittent rotary motion 60 the necessity for a partial reverse motion of both the front and back rollers and the consequently complicated mechanism necessitated thereby are obviated.

65 It will be understood that the details of construction of the mechanism hereinbefore described may be modified without departing from the principle of the invention.

What I claim as my invention and desire to secure by Letters Patent is:—

In a combing machine, the combination of 70 a driving shaft, two pairs of rollers disposed in parallelism with said driving shaft, a spur wheel secured to said driving shaft for rotation therewith, a pair of rigidly connected idler spur wheels one in mesh with 75 said first spur wheel, a pinion carried by the shaft of one of the rollers of one of said pairs in mesh with the other of said idler wheels whereby said roller is continuously 80 rotated during rotation of the driving shaft, a boss carried by said driving shaft for rotation therewith and having a pin extending beyond its periphery, a countershaft in parallelism with said driving shaft and having secured thereto a star wheel adapted to 85 be operated by said pin once for every complete rotation of said boss, a spur wheel secured to said countershaft, an idler pinion in mesh with said spur wheel, an idler spur wheel in mesh with said idler pinion, and a pinion secured to the shaft of one of the 90 rollers of the other pair, whereby said roller is intermittently rotated during rotation of the driving shaft.

In testimony whereof I have signed my 95 name to this specification.

JAMES HORRIDGE.
